UNITED STATES PATENT OFFICE.

MICHAEL P. KENNA, OF DUBUQUE, IOWA.

ENVELOP PRINTING AND ADDRESSING MACHINE.

No. 869,957.

Specification of Letters Patent.

Patented Jan. 16, 1906.

Application filed August 23, 1904. Renewed May 2, 1905. Serial No. 258,505.

To all whom it may concern:

Be it known that I, MICHAEL P. KENNA, a citizen of the United States, residing at Dubuque, in the county of Dubuque and State 5 of Iowa, have invented certain new and useful Improvements in Envelop Printing and Addressing Machines, of which the following is a specification.

My invention relates to envelop printing and addressing machines; and among the objects in view is to provide an envelop-printing machine wherein envelopes may be economically and rapidly printed with different names or addresses or with the ordinary business forms of envelop-printing, said machine being of comparatively simple construction, and wherein the envelopes are automatically fed in succession to stereotype or electrotype plates or rubber-type stamps, which latter are also fed in succession, and the printed envelopes are automatically discharged from the machine.

The invention consists in the novel construction, arrangement, and combination of parts, as hereinafter fully described, illustrated in the drawings, and pointed out in the appended claims.

In the accompanying drawings, Figure 1 is a perspective view of a machine embodying my invention. Fig. 2 is a similar view looking from the opposite end of the machine. Fig. 3 is a detail end view of the roller X and showing the arrangement of the spring-clips for engaging the envelopes and the means for actuating said clips. Fig. 4 is a side elevation of parts of the machine, showing the relative arrangement of the magazine for the printing plates or slugs, the ink-rollers, the printing-rollers, the slug-distributing devices and the endless conveyer belt or chain for the printing plates or slugs. Fig. 5 is a perspective view of parts of the machine, showing more clearly the arrangement of the means for detaching the printing-slugs from the conveyer belt or chain and delivering the same into the galley. Figs. 6 and 7 are detail perspective views showing the manner of detaching the slugs from the conveyer-belt. Fig. 8 is a detail view of one of the printing-slugs. Fig. 9 is a perspective view showing a modified construction of machine. Fig. 10 is a similar view looking from the opposite side of the machine. Figs. 11, 12, 13, and 14 are detail perspective views of parts of the machine.

My present invention embodies certain im-

provements in the machine forming the subject-matter of my copending application filed November 23, 1903, Serial No. 182,381, which improvements will be apparent herein- 60 after.

In the present machine the means for gripping the envelopes and feeding the same in succession to the printing-point comprising the three pairs of spring clips A A B B C C are 65 practically identical with the means shown in my aforesaid copending application, the said clips being actuated by the eccentric band D, secured to upright D', whereby to cause said clips to assume a position to enable them to 70 engage with the flap of the lowermost envelop contained in the receptacle E'. The clips after having been engaged with the flap of the envelop will be released from the frame D and will then close down upon the flap, being 75 actuated by their springs, and will remain in such position and carry the envelop around to the printing-point between the rollers X and Y, and the clips will remain closed upon the flap until after the envelop has moved beyond the printing-point. Then the clips will be again actuated by the frame D to cause them to release the flap of the printed envelop, and the latter will be carried by the endless tapes F, running over pulleys J, and 80 similar to the corresponding tapes in my other pending application, and the tapes F will carry the envelop along and finally drop it into a suitable receptacle. Thus the envelopes are fed from the receptacle E' successively by 85 the clips and conveyed to the printing-point.

G G are brushes arranged and operating similarly to the brushes W in my other application.

In my present case I employ means for 95 feeding the printing-slugs to the printing-point and removing them after having served their purpose, which means I consider an improvement upon the means for similar purposes disclosed in my copending application. 100

K indicates a vertically-arranged receptacle or magazine for the printing-slugs v, which latter are arranged within the magazine one above the other, with their printing-faces upward. The magazine is directly over an endless conveyer-belt L, of sheet metal, which runs around a roller Z and around the roller Y. The outer face of the belt is provided with catches L', arranged at equal distances apart, and they are adapted to engage with 105 the slugs in the magazine as said catches pass beneath the said magazine, detach the lower- 110

- most slug from the rest, and carry the same along to the printing-point. In its revolution the conveyer-belt carries the slug under the inking-rollers N, which are arranged and adapted to ink the printing-faces of the slugs as they pass in succession beneath said rollers, said rollers being carried by standards N', which are adjustable vertically in other standards N² by means of pins n, engaging within slots n' in the standards N². Thus the inking-rollers may be adjusted to bring them into proper inking position.
- For detaching the slugs from the conveyer-belt after the slugs have passed the printing-point and conveying the slugs into galley I provide the following means: O' indicates a trough-shaped chute arranged in an inclined position, with one end lying adjacent to the periphery of the roller Y, said chute being supported by standards Y⁵. The other end of the chute lies adjacent to an inclined galley P. There is sufficient space between the end of the chute and the roller to permit the passage of the catches L'. The end of the chute adjacent the roller has projecting points or prongs O², which lie upon opposite sides of the conveyer-belt and project into circumferential grooves or channels R in the roller Y.
- By the described means the slugs will be caused to be detached from the catches L' in the manner indicated in Figs. 5, 6, and 7, and said slugs will slide down the chute O' and thence into the galley P. I preferably make the galley in sections arranged side by side and adapt said galley to be adjusted transversely, whereby when one section of the galley is filled it may be adjusted laterally to bring another section into position to receive the slugs. The base Q' is provided with a transverse groove Q, into which projects the foot Q² of the support for the galley, so that the galley may be easily slid laterally and guided in their movement.
- Each slug may be provided with a nick v', whereby to indicate when the slugs are in the galley correctly.

In order to make the movement of the conveyer-belt coincide with that of the roller Y, I provide said roller with several sets (three in the present instance) of pins s, arranged at equidistant points about the circumference of the roller, and which pins enter openings T in the conveyer-belt. To give support and direction to the conveyer-belt at and adjacent to the inking-rollers, I provide a support u, of sheet metal, having turned-up edges to give strength and forming a guideway for the belt, said support being securely attached to the standard for the inking-rollers, and the belt and slugs move within and over the support, and the impact of the slug with the ink-rollers is invariably secured.

The slugs are constructed with a slight extension v'' at either end, which extensions

slide within the channels R of the roller Y. These projections also preserve the printing-faces of the slugs from injury when piled up in the magazine.

The roller X is provided with a covering H, of rubber, for receiving the pressure of the printing impression. A removable cap K¹² may be provided for the upper end of the magazine K.

In Figs. 9 to 14 I show a slightly-modified construction of machine, and in this construction I provide a continuous link chain A', arranged and traveling in a manner similar to the belt L in the first-described construction. The link chain, provided with lugs l'' for engaging the slugs v'', is conveyed through channels C' in the rollers X'', Y'', and chute C''. K'' is the receptacle for the slugs. N'' represents the printing-rollers carried by standards N¹⁰. F¹⁰ are the tapes for conveying the printed envelops to a suitable receptacle, said tapes running over pulleys J¹⁰. F¹⁰ is a roller around which the chain A' passes. In the modified construction the envelop-receptacle K' is arranged at an inclination and angled at K''. The feeder for the envelops comprises an inclined channel-shaped guide or chute L', made of tin or other metal, having the parallel sides L² of a width to correspond with the opening K'' in the envelop-receptacle K'. At each end of the ends rollers L³, carrying continuous tapes S' S', are secured, the parts being so constructed that the tapes pass over and under the floor L⁴. The tapes are operated by means of the cam T', mounted on the shaft, carrying the roller X'', upon which cam bears a lever T'', mounted on the end T¹² of the lower roller L³, which also carries a ratchet-wheel T³, and with the teeth of the ratchet engages a spring-actuated pawl T⁵. The envelops are supplied by the tapes S' through the medium of the cam-and-ratchet attachment to the grasp of each succeeding series of spring-clips C¹⁰. The inclination required at which to operate this envelop-feed supply is about thirty degrees, the envelops being guided to the opening in the receptacle K' and thence to the place of contact with the spring-clips C¹⁰ by gravity and the action of the tapes. In Fig. 12 I show another construction of envelop-feed supply, which is constructed in a similar channel-approach w, the floor or bottom w¹⁵ being of sheet-tin or other suitable material and curved, as shown at M¹⁵. The approach w is connected with the receptacle K¹⁵ at an inclination of about forty-five degrees, the envelops being fed directly to the opened end w² and allowed to slide by gravity into the receptacle, that movement being checked slightly by the top of the curve M¹⁵ lessening the weight bearing immediately over the place of contact with the spring-clips A²⁰, reducing the liability of more than one of the envelops at a time slip-

ping out of the bottom of the receptacle and permitting the action of the brushes G^{15} in beating back other envelops. The object of the improvement in the envelop-feed supply 5 is to obviate the vertical weight sustained by the bottom envelops when acted upon by the spring-clips, the pressure frequently forcing more envelops than the one required from the receptacle and at times more than the 10 brushes could sweep back. The improved feed device by spreading the envelops within the channel-approach reduces their pressure and overcomes the said objection. In the construction seen in Fig. 11 G'' indicates the 15 brushes, X'' the upper roller, and C^{10} the spring-clips, while in Fig. 12 G^{15} indicates the brushes, X^{15} the upper roller, A^{20} the spring-clips, L^{15} the parallel side of the approach w . For the purpose of relieving a possible friction 20 on the bottom of the lowermost envelop I insert short wires 1 and 2 on the floor of the receptacle. This floor is made to present as little obstruction as possible by leaving free 25 passages for the action of the spring-clips and the free movement of the roller thereunder. I may, and preferably do, reverse the position of the slug-feed supply, and Fig. 13 shows the row of slugs facing the printing-roller, and I remove the roller Y'' and its supporting-standards to at least the distance of 30 one length of chain between two brackets for the purpose of having them set directly over the chute C'' instead of having them drop upon the moving roller. I also show the 35 mode of conveying each slug to its place under the printing-roller. The slugs are retained in the receptacle K^{15} by its sides, the back and narrow sides K^{16} extending downward only so far as will allow one slug at a 40 time free movement. The slug is taken forward by the engaging lugs successively as they reach it and is carried over the chute C^{15} , through the guideways C'' , to its destination, and thence carried off to the galleys, as 45 previously described.

I may use in connection with the extended full-length metal roller X electrotype or stereotype plates X^{20} for printing the envelops, corner-sections, or other like details, 50 adapting it for that purpose by constructing parallel to its length on its outer circumferential surface six (more or less) beveled orifices X^2 at convenient distances apart for the reception of wooden wedges X^3 , having coinciding beveled edges. Upon the wedges I will tack electrotype or stereotype plates, 55 securing them to the wedges where required. Fig. 14 shows the parts just hereinbefore described.

The machine will in practice be made of various sizes to accommodate various sizes of envelops.

What I claim is—

1. In a machine of the character described, 125 i.e combination with two superposed rollers,

of a conveyer belt or chain passing between the rollers, a magazine for printing-slugs, means carried by the belt for engaging the slugs and carrying them between the rollers, and inking devices intermediate the magazine and the said rollers. 70

2. In a machine of the character described, the combination with two superposed rollers, 75 of a conveyer belt or chain passing between the rollers, a magazine for printing-slugs arranged above the belt, catches carried by the belt adapted to engage the slugs and carry them between the rollers and inking devices intermediate the magazine and the said rollers. 80

3. In a machine of the character described, the combination with two superposed rollers, 85 of a conveyer belt or chain passing between the rollers, a magazine for printing-slugs, means carried by the belt adapted to engage the slugs and carry them between the rollers, a support over which the conveyer-belt travels and inking devices arranged at a point adjacent to and above the said support. 90

4. In a machine of the character described, 95 the combination with two superposed rollers, of a conveyer belt or chain passing between the rollers, means for effecting the engagement of one of the rollers and the belt as the latter travels around said roller, a magazine 95 for printing-slugs, means for effecting the engagement of the belt and the slugs, and inking devices intermediate the magazine and the rollers. 100

5. In a machine of the character described, 100 the combination with two superposed rollers, of a conveyer belt or chain passing between the rollers, a magazine for printing-slugs, means for effecting engagement of the belt with the slugs, inking devices intermediate 105 the magazine and rollers, an inclined chute arranged to effect the disengagement of the slugs from the belt and a galley into which the chute is adapted to discharge the disengaged slugs. 110

6. In a machine of the character described, 115 the combination with two superposed rollers, of a conveyer belt or chain passing between the rollers, a magazine for printing-slugs, means for effecting engagement of the belt with the slugs, inking devices intermediate 120 the magazine and the rollers, an inclined chute arranged to effect the disengagement of the slugs from the belt, and a transversely-adjustable galley into which the chute is adapted to discharge the disengaged slugs. 125

7. In a machine of the character described, 125 the combination with two superposed rollers, the lower one of which is provided with circumferential grooves, of a conveyer belt or chain passing between the rollers, a magazine for printing-slugs, means for effecting engagement of the belt and slugs, an inclined chute provided with projecting points or spurs adapted to enter the grooves in the roller, and 130

a galley into which the chute is adapted to discharge the disengaged slugs.

8. In a machine of the character described, the combination with two superposed rollers, 5 the lower one having circumferential grooves, of a conveyer belt or chain passing between the rollers, a magazine for printing-slugs, each slug having extensions at the ends to travel in the grooves of the roller, means for 10 effecting the engagement of the belt with the slugs, an inclined chute having projecting points or spurs adapted to enter the grooves in the roller and to disengage the slugs from the belt and a galley into which the chute is 15 adapted to discharge the disengaged slugs.

9. In a machine of the character described, the combination with two superposed rollers, 5 of a conveyer belt or chain passing between the rollers, a magazine for printing-slugs, 20 means carried by the belt for engaging the slugs and carrying them between the rollers, inking devices intermediate the magazine and the said rollers, an envelop-receptacle arranged with its discharge end adjacent to the 25 circumference of the upper roller, clips carried by the upper roller and means for feeding the envelops successively into a position to be grasped by the said clips, and means for operating the clips in the manner and for 30 the purpose specified.

10. In a machine of the character described, the combination with two superposed printing-rollers, of a conveyer belt or chain passing between the rollers, a magazine 35 for printing-slugs, means carried by the belt for engaging the slugs and carrying them between the rollers, inking devices intermediate the magazine and the said rollers, an en-

velop-receptacle arranged at an inclination with its discharge end adjacent to the circumference of the upper roller, clips carried by the upper roller, feed-tapes arranged to convey the envelops along the receptacle, means for imparting a step-by-step movement to the tapes and means for operating 45 the clips in the manner and for the purpose specified.

11. In a machine of the character described, the combination with two superposed printing-rollers, of a conveyer belt or 50 chain passing between the rollers, a magazine for printing-slugs, means carried by the belt for engaging the slugs and carrying them between the rollers, inking devices intermediate the magazine and the said rollers, an envelop-receptacle arranged at an inclination with its discharge end adjacent to the circumference of the upper roller, clips carried by the upper roller, feed-tapes arranged to convey the envelops along the receptacle, 55 rollers at the ends of the receptacle and upon which the said tapes run, a ratchet-wheel on the shaft of the lower roller, a lever also mounted at one end on the said shaft, a cam on the shaft of the upper printing-roller and 60 upon which cam the opposite end of the lever bears and a pawl on said lever engaging the ratchet-wheel, all arranged for coöperation 65 as described.

In testimony whereof I affix my signature 70 in presence of two witnesses.

MICHAEL P. KENNA.
